Primary Examiner — Susan E Krakower*Assistant Examiner* — Kendra L Hamilton(74) *Attorney, Agent, or Firm* — Li & Cai Intellectual Property (USA) Office(57) **CLAIM**

The ornamental design for a “baby bottle holder,” as shown and described.

DESCRIPTION

FIG. 1 is a perspective view of a baby bottle holder showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 of FIG. 6;

FIG. 9 is a cross-sectional view taken along line 9-9 of FIG. 6; and,

FIG. 10 is a perspective view showing the practical usage thereof.

The broken lines depict portions of the baby bottle holder which form no part of the claimed design.
